ASSIGNMENTS, TO JAMES R. GARFIELD, TRUSTEE, OF CLEVELAND, OHIO.

TELEPHONE SYSTEM.

1,223,369.

Specification of Letters Patent. Patented Apr. 24, 1917.

Application filed August 18, 1905. Serial No. 274,765.

To all whom it may concern:

Be it known that I, EDWARD E. CLEMENT, a citizen of the United States, residing at Washington, in the District of Columbia, have invented certain new and useful Improvements in Telephone Systems, of which the following is a specification, reference being had therein to the accompanying drawings.

10 My invention relates to telephone systems and particularly to exchange systems employing common battery. It has for its object the simplification of the exchange switchboard and its method of operation.

15 The salient features of my invention are: A switchboard without answering jacks, and having what are known as single cord terminals, instead of pairs of plugs and cords. Each cord circuit terminates at one end in a 20 plug and at the other end in an automatic switch containing line terminals corresponding to the answering jack terminals on an ordinary switchboard. When a line calls its answering terminal in each of the automatic switches to which it is multiplied becomes busy, and the switch thereupon turns 25 its arm to the contacts of the calling line, where they stop, thereby connecting the said calling line with the cord circuit and its terminal plug. A signal is associated with the 30 cord and is displayed when the subscriber connects therewith. It will be obvious that I may have all the subscribers' lines in a particular group multiplied to all the cord 35 circuits associated with that group, or I may split up the subscribers among widely separated cord switches, in such fashion that calls will be more or less uniformly distributed among the cords and among the 40 operators.

My invention is illustrated in the accompanying drawings in which Figure 1 is a diagram showing two subscribers' stations and the cord circuit apparatus at the central 45 station for connecting them; and Fig. 2 is a supplemental diagram showing subscribers' lines multiplied into a plurality of switches and thereby gaining access to a plurality of link circuits. Fig. 2 also shows the wipers 50 of different switches set angularly apart around the spindle, so that no two switches will test the same line at the same time.

In the drawing A and A' are two sub-

scribers' stations each provided with the usual talking and signaling apparatus, which 55 of itself forms no part of the present invention. At each station when the talking apparatus is in use the circuit of the line is completed through the switch hook, and when not in use the circuit for ringing current is completed through a condenser and the switch hook. As both lines 1-2 and 3-4 are identical I will describe only the first. The wires 1 and 2 terminate at the central office upon contacts n , n' of the cut-off relay N which normally connects them to branches 9, 10 leading respectively to the line relay M and thence by wire 12 to the main battery B, for the former, and by wire 10 to ground for the latter. The relay M 65 through its armature m controls the connection of battery through wire 12 to branch 11 and the test terminals j^4 of the switch P. When the cut-off relay N is energized, it 70 divorces the line wires from the calling branches 9 and 10 and puts them onto the talking branches 5 and 6, leading respectively to the sleeve and spring contacts j and j' of the multiple jacks J, and to corresponding contacts j^2 , j^3 in the switch P. I 75 have indicated the contacts of the switch collectively by the letter J', because these contacts correspond to the answering jacks of the ordinary switchboard.

The switch P comprises a spindle p carrying the contact wipers p^8 , p^9 , p^{10} , which as the spindle is rotated sweep over the circular periods of contacts J', thus making contact successively with the set belonging to each line on that switch. The 85 spindle is arranged to be constantly rotated by means of a driving shaft and pulley p' shown as receiving their motion from a belt. To the driving shaft the spindle p is normally connected by the coupling p^2 , p^3 , 90 which comprises the part p^2 fixed on the driving shaft and the complementary part p^3 splined on the spindle. It is intended that when the coupling is disengaged the spindle shall be stopped instantly, and for 95 this purpose a fixed stop p^4 is provided, against which the lower roughened face of the clutch disk impinges as its upper roughened face leaves the part p^2 . The coupling and uncoupling is accomplished through the 100 medium of a magnet p^6 controlling an ar-

mature lever p^5 normally drawn back by a stiff spring p^7 and having its end engaging in an annular groove between the clutch disks. When the magnet is deenergized the 5 spindle is constantly driven. When the magnet is energized the spindle is instantly stopped.

Upon the spindle are three insulated collars carrying the three wipers p^8 , p^9 , p^{10} , 10 and upon each collar rests a contact spring p^{11} , p^{12} , p^{13} , these forming the terminals of the cord conductors. Spring p^{12} goes to cord conductor 15, thence to the condenser C and thence for talking purposes by conductor 15 to 17 to the tip of the calling plug P'. The spring p^{13} goes to wire 16, by condenser C' to wire 18 and to the sleeve of the calling plug P'. Spring p^{11} goes to the wire 20 thence to the normally closed back contacts of the 20 cord circuit relay S³, thence by wire 21 to the normally closed back contact of relay S thence by wire 19 to magnet p^6 and also to lamp s and ground through wire 31. The 25 relays S and S² are in a bridge 23, 24 across the answering end 15, 16 of the cord circuit, with a main battery B between them; while the relays S' and S³ are in a similar bridge 27, 28 across the calling end 17, 18 of the 30 cord circuit, and also with the battery between them.

The circuit connections remaining unmentioned will best be understood by the following statement of operations.

Suppose subscriber A desires to be connected with subscriber A'. He removes his receiver from the hook, thereby closing his line circuit, and causing current to flow through the following path: B, 12, M, 9, n, 1, substation, 2, n', 10, and ground to B. 35 Relay M thereupon pulls up and puts the battery on contacts j^4 through wires 12, 11. The switches P are constantly driven, and are preferably driven off the same shaft, so that they are not only all moving at the same 40 rate of speed, but the wiper arms are set in successive angular positions, so that no two switch arms will come on the same contact at the same instant. The first switch arm p^8 arriving at a contact j^4 of the calling line completes the circuit as follows: B, 12, 45 11, j^4 , p^8 , p^{11} , 20, 21, 19, p^6 and ground; also from 21 through the armature of S to s, 31, and through the armature of S³ to ground. The magnet p^6 instantly pulls up 50 and the lamp s lights. When the magnet pulls up it disengages the clutch p^3 , from the revolving part p^2 and engages it with the stop p^4 , the spindle and its contacts then 55 remaining stationary resting upon the contacts of the calling line. The lamp s lights and continues to burn until the operator completes the connection by inserting the calling plug P' in the jack J in the line 3, 4. The operator has a listening and ringing 60 key of the ordinary type, and by means 65

thereof ascertains from the calling subscriber the number wanted. She then tests the jack J, and inserts the plug P' ringing the wanted subscriber A' in the usual manner. As soon as the spindle stopped a circuit was completed for the relay S² as follows: B, 26, S², 24, 16, p^{13} , p^{10} , j^2 , N, and ground. This circuit at once energizes the cut-off relay N, which pulling up disconnects the line relay M, and puts the line 70 wires 1, 2 on the talking wires 5, 6. The metallic circuit being then completed the relay S takes current instantly over the following path: B, 26, S², 24, 16, p^{13} , p^{10} , j^2 , 6, n', 2, substation, 1, n, 5, j^3 , p^9 , p^{12} , 15, 23, S, 80 ground at 25. This pulls up the armature of S, and completes the local circuit for the magnet p^6 as follows: B, 26, armature of S², 22, armature of S, 19, p^6 and ground. The lamp s also takes current from the same 85 source and remains lighted, but it will be observed that having thus connected with the line the switch has taken control thereof, and except for the cut-off relay the line is clear in to the cord circuit. Now, when the 90 plug P' is finally inserted in the wanted line jack, the relay S³ takes current from the battery through cord conductor 18 and the line conductor 8 to cut-off relay N and ground. Pulling up its armature, the relay 95 S³ disconnects the wire 20, puts battery on wire 29 for the supervisory signal s' and takes the ground off the wire 31 from the lamp s. In other words, the calling lamp signal is extinguished and retired by the act 100 of the operator in completing the connection.

When the subscribers have finished and hang up, the two relays S and S' lose current and let go their armatures. This on the part 105 of the former breaks the battery circuit to the magnet p^6 , which thereupon lets go its armature, throws back the clutch and starts the spindle p to rotating again with constant rapidity. The instant the wipers pass 110 off the line contacts j^2 , j^3 , the relay N loses current, and the line conditions shown in the drawing are restored, subscriber A being then free to make another call. On the other hand, relay S' when it releases completes the circuit of the supervisory lamp s' 115 as follows: B, 26, 29, 30, s' and ground. The subscriber A' cannot be hung up therefore because if the operator carelessly leaves the plug in the jack he can call her attention 120 by flashing the lamp.

It is to be understood that each switch P contains the terminals of a large number of lines, as for instance 100. I contemplate connecting these lines so that the same group 125 will not appear together in more than one switch, that is if each line has 10 multiples, the first 100 lines may have their number one multiple terminals grouped together in the same switch P, but all their other mul- 130

multiple terminals would be divided up among nine other switches, or more according to the size of the exchange.

I do not limit myself herein to the specific form of switch shown nor to the specific line or cord circuits. The principle involved may be applied in a variety of ways, and I shall claim the same broadly.

Having thus described my invention what I claim and desire to secure by Letters Patent is:

1. In a telephone exchange system, the combination with a group of telephone lines extending from sub-stations to an exchange, of a plurality of cord connectors at the exchange, each including a manually operated terminal plug at one end of the cord circuit and having a traveling switch at the other end of the cord circuit with its wiper sweeping over fixed line contacts, means for driving said switches simultaneously with their wipers angularly displaced in sequence, whereby no two wipers will touch contacts of the same line simultaneously, and means serving to arrest the operation of a traveling switch and cause it to connect a cord circuit with the telephone line of a calling subscriber.

2. In a telephone exchange system, the combination with a group of telephone lines extending from sub-stations to an exchange, of a plurality of cord connectors at the exchange, each including a manually operated terminal plug at one end of the cord circuit and having a traveling switch at the other end of the cord circuit with its wiper sweeping over fixed line contacts, means for driving said switches simultaneously with their wipers angularly displaced in sequence, whereby no two wipers will touch contacts of the same line simultaneously, and means serving to arrest the operation of a traveling switch and cause it to connect a cord circuit with the telephone line of a calling subscriber, and a signal at the exchange controlled by said subscriber's apparatus to indicate the fact of his connection with a cord circuit.

3. In a telephone exchange system, the combination with a group of telephone lines extending from sub-stations to an exchange, of a plurality of link connectors at the exchange, each including a manually operated terminal at one end of the link circuit and having a traveling switch at the other end of the link circuit, with its wiper sweeping over fixed line contacts, means for driving said switches simultaneously with their wipers angularly displaced in sequence, whereby no two wipers will touch contacts of the same line simultaneously, and means serving to arrest the operation of a traveling switch and cause it to connect a link circuit with the telephone line of a calling subscriber.

4. In a telephone exchange system, the combination with a group of telephone lines extending from sub-stations to an exchange, of a plurality of link connectors at the exchange, each including a manually operated terminal at one end of the link circuit and having a traveling switch at the other end of the link circuit with its wiper sweeping over fixed line contacts, means for driving said switches simultaneously with their wipers angularly displaced in sequence, whereby no two wipers will touch contacts of the same line simultaneously, means serving to arrest the operation of a traveling switch and cause it to connect a link circuit with the telephone line of a calling subscriber, and a signal at the exchange controlled by said subscriber's apparatus to indicate the fact of his connection with a link circuit.

5. A telephone exchange system whose telephone lines have connecting jacks and have cord circuits provided with connecting plugs for insertion within said jacks, selective switching mechanism in circuit relation with the lines for uniting calling telephone lines with idle cord circuits and including traveling answering terminals of the cord circuits and multiplied telephone line terminal contacts engaged by said answering terminals, means for driving a plurality of said answering terminals simultaneously but in sequence with respect to their path of travel, and calling subscribers' supervisory signaling apparatus connected with the cord circuits, substantially as described.

6. A telephone exchange system whose telephone lines have connecting jacks and have cord circuits provided with connecting plugs, selective switching mechanism in circuit relation with the lines for uniting calling telephone lines with idle cord circuits and including traveling answering terminals of the cord circuits and multiplied telephone line terminal contacts engaged by said answering terminals, means for driving a plurality of said answering terminals simultaneously but in sequence with respect to their path of travel, and relay mechanism connected with each cord circuit and governing the selective switching mechanism to release the same, substantially as described.

7. In a telephone exchange system, the combination with a plurality of telephone lines extending from sub-stations to an exchange, of cord connectors at the exchange for uniting telephone lines in telephonic connection, each connector having a manually operated terminal plug, while each line has a switch for receiving said plug, traveling switches also constituting terminals of said cord connectors, multiplied terminals of said lines arranged in co-operative relation with said switches, means for driving a plurality of said switches simultaneously but out of line with each other, so that no two switches

- will come upon multiple terminals of the same line simultaneously, and means for arresting said switches when connected with the terminals of a calling line, substantially as described.
- 5 8. In a signaling system, the combination with a plurality of subscribers' stations, of cord circuits to which said stations are adapted to be connected, the number of said 10 cord circuits being less than the number of the said subscribers' stations, selective means corresponding in number to that of the said cord circuits for connecting any of said stations with any of said cord circuits and continuously driven means for actuating said 15 selective means in common, with connecting means for each selective means, arranged to produce sequential travel, whereby no two stations can be connected to the same cord circuit.
- 20 9. In a signaling system, the combination with a subscriber's station, of signaling conductors and a set of movable contacts fixed with relation to each other, a signal whereby a subscriber indicates a desire for 25 communication, and means for controlling said movable contacts, said set of movable contacts comprising contacts for connecting said signaling conductors with said subscriber's 30 station and a contact adapted to close a circuit through said means for controlling the said set of contacts and through said signal simultaneously with the connection of the subscriber's station with the signaling conductor and means actuated by current in 35 the signaling circuit for closing a local circuit through said signal and means for controlling said movable contacts but not passing through any of the contacts of said set.
- 40 10. In a signaling system, the combination with a subscriber's station, of signaling conductors, a signal for indicating the desire of the subscriber for connection, a set of movable contacts fixed with relation to each 45 other, a "common" battery adapted to supply signaling current to connected stations, and means for controlling said movable contacts, said set of movable contacts comprising contacts for connecting said signal conductors with said subscriber's station and a contact adapted to close circuits through said "common" battery, said signal and said 50 means for controlling said movable contacts simultaneously with the connection of the subscriber's station with the signal conductor and means actuated by current in the signaling circuit for closing a local circuit through said common battery, said signal and said means for controlling the movable contact but not passing through any of the contacts of said set.
- 55 11. In a signaling system, the combination with a subscriber's station, of signaling conductors and a set of movable contacts fixed with relation to each other, a signal

whereby a subscriber indicates a desire for communication, and means for controlling said movable contacts, said set of movable contacts comprising contacts for connecting said signaling conductors with said subscriber's station and a contact adapted to close a circuit through said means for controlling the said set of contacts and through said signal simultaneously with the connection of the subscriber's station with the signaling conductors and contacts at the subscriber's station for controlling the circuit through the means for controlling the said set of movable contacts.

70 12. In a signaling system, the combination with a subscriber's station, of signaling conductors and a set of movable contacts fixed with relation to each other, a signal whereby a subscriber indicates a desire for communication, and means for controlling said movable contacts, said set of movable contacts comprising contacts for connecting said signaling conductors with said subscriber's station and a contact adapted to close a circuit through said means for controlling the said set of contacts and through said signal simultaneously with the connection of the subscriber's station with the signaling conductors, the said signal and the said means for controlling the said set of contacts being connected in parallel and contacts at the subscriber's station for controlling the circuit through the means for controlling the said set of movable contacts.

75 13. In a signaling system, the combination with a subscriber's station having a receiver hook, of signaling conductors and a set of movable contacts fixed with relation to each other, a signal whereby a subscriber indicates a desire for communication, and means for controlling said movable contacts, said set of movable contacts comprising contacts for connecting said signaling conductors with said subscriber's station and a contact adapted to close a circuit through said means for controlling the said set of contacts and through said signal simultaneously with the connection of the subscriber's station with the signaling conductors and contacts at the subscriber's station actuated by the receiver hook for controlling the said means for controlling the said set of movable contacts.

80 14. In a signaling system, the combination with a subscriber's station having a receiver hook, of signaling conductors and a set of movable contacts fixed with relation to each other, a signal whereby a subscriber indicates a desire for communication, and means for controlling said movable contacts, said set of movable contacts comprising contacts for connecting said signaling conductors with said subscriber's station and a contact adapted to close a circuit through said means for controlling the said set of contacts.

contacts and through said signal simultaneously with the connection of the subscriber's station with the signaling conductors and contacts at the subscriber's station actuated by the receiver hook for controlling the said means for controlling the said set of movable contacts.

15. In a signaling system, the combination with a plurality of subscribers' stations, 10 of signaling conductors extending from each of said stations, selective conductors corresponding to each subscriber's station, other sets of signaling conductors, selective devices for connecting the conductors extending 15 from the subscribers' stations with the said other sets of signaling conductors, the signaling and selective conductors corresponding to each station being connected with each of the said selective devices, a circuit 20 for each of the selective devices adapted to control its movement, the circuits for controlling the movement of the selective devices being adapted to be initially closed through one of said selective conductors and 25 means for breaking the circuit through the last mentioned conductor upon the establishment of the signaling circuit through a selective device.

16. In a telephone exchange system, the combination with a plurality of lines, of a lesser plurality of link circuits, traveling switches, one for each link circuit, a terminal of each line in the path of each of said switches, means for causing all idle answering 35 switches to pass in succession over the terminals of any given line, means made active in initiating a call in any one of said lines for automatically causing the first arriving one of said answering switches to 40 stop and make connection therewith, means for preventing any other switch from establishing a connection with the terminals of a line already engaged, means for subsequently releasing a connected switch, and 45 means for making it available for the common use of the other lines only after it has resumed its proper sequential position among the other idle answering switches in their relation to the terminals of any given 50 line.

17. In a telephone system the combination with a plurality of lines, of connecting circuits, less in number than the lines, a plurality of calling line finders, one for each 55 connecting circuit, means for simultaneously moving them, means for always maintaining them in fixed relation out of line with each

other during their movement, terminals of all the lines positioned so as to be engaged in succession by all of the moving calling-line 60 finders, means for causing a single calling line finder to stop in engagement with the terminal of a calling line, and means for so changing the condition of an engaged terminal as to prevent any other calling line 65 finder from stopping in engagement therewith.

18. In a telephone exchange system, a plurality of telephone line terminals, a lesser plurality of idle link circuit brushes, means 70 for simultaneously moving all of said link circuit brushes so that each brush always approaches the terminals of a plurality of lines from which the preceding brush is receding, whereby the terminal of any line will be 75 engaged by one of said traveling brushes in a relatively small movement thereof, and means for stopping any one or more of said traveling brushes independently of the others.

19. In a telephone exchange system, the combination with a plurality of coöperating movable switches, of means for moving them, a greater plurality of relatively stationary circuit contacts with any of which 85 any of said movable switches may connect, means for maintaining a sequential relation between the positions of all moving switches such that each moving switch next approaches the terminal of a different circuit, and means for permitting any one of 90 said movable switches to remain in engagement with a stationary contact independent of the movement of the others and later to 95 continue its movement in its proper sequential relation thereto.

20. In a telephone exchange system, a plurality of line contacts, a plurality of idle link circuits, a traveling contact for each link circuit adapted to approach each line contact once in each cycle of the traveling contacts, said traveling contacts being so distributed among the line terminals that all of them always approach contacts of different lines at each successive stage of a cycle of 105 movement, and means for stopping one or more of said traveling contacts independently of the others.

In testimony whereof I affix my signature in presence of two witnesses.

EDWARD E. CLEMENT.
